(57) CLAIM

The ornamental design for a packaging sleeve for a bottle as shown and described.

DESCRIPTION

FIG. 1 is a back perspective view of a packaging sleeve for a bottle showing my new design in an environment of use;

FIG. 2 is a front view thereof;

FIG. 3 is a back view thereof;

FIG. 4 is a left side view thereof, the right side being a mirror image thereof;

FIG. 5 is a top view thereof;

FIG. 6 is a bottom view thereof;

FIG. 7 is an enlarged detailed view of the center portion of FIG. 4, the opposite side being a mirror image thereof; and, FIG. 8 is an enlarged detailed view of the center portion of FIG. 3.

The broken lines showing a bottle in FIGS. 1-3 illustrate environment and form no part of the claimed design.

1 Claim, 8 Drawing Sheets
